Primary Examiner — Robert A Delehanty(74) *Attorney, Agent, or Firm* — Alan D. Borelli, Esq.; Robert Z. Evora, Esq.(57) **CLAIM**

The ornamental design for an infant bath tub, as shown and described.

DESCRIPTION

FIG. 1 is a top view of an infant bath tub of our new design;

FIG. 2 is a side view thereof;

FIG. 3 is a front view thereof;

FIG. 4 is an upper perspective view thereof;

FIG. 5 is a lower perspective view thereof; and,

FIG. 6 is a side cross-section view at 6-6 in FIG. 1 thereof. The broken lines shown in the drawings represent environmental structure in FIGS. 1-6 that form no part of the claimed design.

1 Claim, 6 Drawing Sheets(56)
